HIGH-FREQUENCY ELECTRON TUBE
STRUCTUREWilliam W. Hansen, Garden City, N. Y., assignor
to The Sperry Corporation, a corporation of
Delaware

Application June 28, 1945, Serial No. 602,007

11 Claims. (Cl. 315—6)

1

The present invention relates to the art including high frequency electron discharge devices, circuits and methods and, more particularly, to such methods, circuits and devices adapted to operate at super-high frequencies of the order of 10^8 megacycles per second or higher.

The present application is a continuation-in-part of prior copending application Serial No. 416,170, filed October 23, 1941, now Patent No. 2,425,738 granted August 19, 1947, for Tunable High Frequency Electron Tube Structure.

In one embodiment, the invention more specifically relates to frequency multiplier devices adapted to convert lower frequencies into such super-high frequencies. The present invention is more particularly directed to devices utilizing cavity resonators in inductive relation to grouped or variable-current electron streams for the purpose of extracting such super-high frequency energy from these streams.

In prior Patent No. 2,281,935, granted May 5, 1942, in the names of R. H. Varian and W. W. Hansen, the present inventor, there is disclosed one type of frequency multiplier in which a constant-current electron stream of uniform electron velocities is varied periodically in velocity (velocity-modulated) at a fundamental frequency. The velocity-modulated stream is thereafter passed through a field-free drift space within which the uniform-current, variable-velocity electron stream is converted into a variable-density or variable-current electron stream, sometimes termed a "density-modulated" electron stream, by the velocity-grouping action incident to faster electrons overtaking slower electrons. This variable-current stream is then passed through an output cavity resonator in inductive relation thereto, which resonator, being tuned to a super-high harmonic frequency of the predetermined fundamental frequency, serves to extract harmonic frequency energy from the stream for use as desired.

One major feature of the present invention resides in the modification of such a frequency multiplier permitting its use for high ratios of frequency multiplication with markedly increased efficiency. According to the present invention, the magnitude of the electron current is varied periodically at the same fundamental frequency as that at which the electron velocities are varied, before passage of the electron stream through the field-free drift space or drift tube, in distinction to the prior art devices where the electron current magnitude was left unchanged before entering the drift space. In the present de-

vice, the current variation is performed simultaneously and cophasally with the velocity modulation. It has been found that the harmonic frequency energy content of the stream after passage through the drift tube is thereby materially increased, providing increased power output from the output resonator for a given input fundamental frequency voltage amplitude or, from another point of view, permitting equivalent output with smaller input. Since in prior art devices the ratio of output-to-input frequencies, termed the frequency multiplication ratio, is limited by the fact that for higher ratios the output is very small, the devices of the present invention permit higher ratios to be used, since the output amplitudes at such output frequencies are materially increased.

A further feature of the invention resides in the application of the fundamental frequency input voltage directly between the cathode and an adjacent electron-accelerating electrode, with this fundamental frequency voltage superposed upon the electron-accelerating voltage, thereby producing simultaneous and combined current variation and velocity modulation of the electron stream, which is followed by velocity-grouping of the electrons of the stream in a field-free drift space, resulting in a type of electron grouping especially highly desirable in frequency multiplying devices and adapted to produce substantial amounts of output power at the super-high multiplied output frequency.

Still another feature of the present invention resides in constructional features for devices of the above-described type, especially adapted to produce the improved results characteristic of the present invention.

These and other features of the invention will become apparent from the following detailed description and the appended drawings, in which:

Fig. 1 represents a schematic circuit diagram of the present improved electron discharge device and its circuit;

Fig. 2 shows a longitudinal view, partly in cross-section, of one form of the electron discharge device of the present invention;

Fig. 2A shows a fragmental cross-sectional view of the device of Fig. 2, taken along line A—A thereof, and showing in plan view one form of grid which may be used in this device; and

Fig. 3 shows a longitudinal cross-sectional and partly schematic view of a modified form of the invention.

Referring to the drawings, in Figs. 1 and 2 there is shown a cathode 11 of any suitable con-

2

ventional type adapted to supply free electrons. Cathode 71 may include conventional focussing and control electrodes. Adjacent to cathode 71 is an electron-permeable grid or accelerating electrode 69. Connected between cathode 71 and grid 69 is a suitable unidirectional voltage source 68 having its negative terminal connected in a manner to be described below to cathode 71 and its positive terminal connected to grid 69. Cathode 71, grid 69, and potential source 68 serve to form the stream of electrons projected through grid 69.

Surrounding the path of the electron stream beyond grid 69 is a drift tube 75 providing a field-free drift space therewithin. Drift tube 75 is conductively connected to and supports grid 69. Grid 69 and tube 75 are preferably grounded as at 67. The far end of drift tube 75 supports a similar grid 66 which is adjacent to a corresponding grid 65, thereby providing a narrow output gap between grids 66 and 65. The electron stream after passing through grids 66 and 65 is collected on the conducting end wall of the device, such as at 91, or by any other conventional electron-collecting means.

The grids 66 and 65 form portions of the walls of an output cavity resonator 89. As shown in Fig. 2, resonator 89 may be formed with a flexible wall 88 so that its resonant frequency may be adjusted by suitable tuning screws 93 controlling the separation between grids or output electrodes 66 and 65. Any other type of tuning means may be used for resonator 89, or it may be manufactured as fixed-tuned at the desired output frequency.

Resonator 89, collector wall 91, drift tube 75, and wall 87 connected thereto preferably form part of the evacuated enclosure or envelope for the electron discharge device. Cathode 71 is suitably supported in insulated fashion within this envelope as by a glass or insulating end bell or seal 78 completing the envelope.

In operation, the fundamental frequency voltage to be frequency-multiplied is superposed on the voltage of source 68 impressed between cathode 71 and grid 69, so that the cathode-grid voltage is a unidirectional voltage pulsating at the fundamental frequency. One manner of applying this fundamental frequency voltage between electrodes 71 and 69 is shown in Fig. 1, although other methods may be used, as in Figs. 2 and 3, described below. Thus, a parallel-resonant lumped-constant circuit comprising parallel-connected inductance 71 and capacitance 73 is connected between the negative terminal of source 68 and cathode 71. Source 68 may be suitably bypassed with respect to alternating currents, if desired, as by a conventional by-pass condenser 80 connected thereacross. Inductance 71 forms the secondary of a radio frequency transformer whose primary winding 83 is inductively coupled to winding 71. Primary winding 83 is supplied with the fundamental frequency to be multiplied, in any convenient manner. An illustrative source of fundamental frequency might be a low radio frequency source 72 feeding a frequency multiplier 74 of conventional type, the frequency of source 72 and the multiplication ratio of multiplier 74 being selected to provide the desired fundamental frequency f . For example, source 72 might be a crystal-controlled oscillator to provide frequency-stabilized operation.

Although the series fed resonator 71, 73 shown in Fig. 1 differs from the unity coupled feed struc-

ture shown in Fig. 2, it will be understood that the two circuits are equivalent. As shown in Fig. 2, inductance 71 comprises a single loop of hollow tubular conductor having one end grounded by connection to drift tube 75 and the other end capacitively coupled to cathode 71 by a suitable bypass condenser 79. The leads 81 for the unidirectional or low frequency potentials necessary to operate cathode 71, such as the heater voltage leads and the accelerating voltage supply lead from source 68, are brought in at the grounded end of hollow conductor 71 and extend therein to the heater and cathode. In this way it is unnecessary to insulate these leads 81 with respect to radio frequency voltages, since the tubular conductor 71 acts as a shield, and the entrance point into conductor 71 is made adjacent the point of lowest radio frequency potential. Primary winding 83 is formed of a single loop of wire in inductive relation to conductive loop 71, and is coupled to the fundamental frequency source, such as 74, 72, in any suitable manner.

In operation, resonant circuit 71, 73 is tuned substantially to the input fundamental frequency, and resonator 89 is tuned substantially to a desired harmonic frequency output. The electrons emitted by cathode 71 are then subjected to a unidirectional accelerating electric field provided by source 68, upon which is superposed a fundamental frequency field produced by the voltage across tuned circuit 71, 73. During the positive portions of the fundamental frequency cycle when grid 69 is most positive with respect to cathode 71, a relatively large number of electrons will flow from cathode 71 to grid 69. Also, these electrons will have greater-than-average velocity. At the instants when the fundamental frequency component of the voltage between grid 69 and cathode 71 is zero, an average number of electrons with average velocity will enter the drift tube 75. During the negative portions of the fundamental frequency cycle, when grid 69 is least positive with respect to cathode 71, a minimum number of electrons having lowest velocity will enter the drift tube 75. Accordingly, the electron stream is simultaneously subjected to velocity variation or modulation and current variation or density modulation, and in fixed cophasal relation, since minimum current magnitude and minimum velocity are produced simultaneously.

In frequency multipliers of the velocity-modulation type, such as disclosed in the above-mentioned Patent No. 2,281,935, it has been discovered that the lowest velocity electrons are a drawback in obtaining optimum harmonic frequency energy content in the electron stream, since these minimum-velocity electrons prevent the electron-bunching action from producing an optimum shape of electron bunch for the purpose of producing harmonic frequency energy. Also, the maximum-velocity electrons are most useful in producing harmonic frequency output. By the present invention the number of these harmful minimum-velocity electrons is reduced, since the electron current is a minimum simultaneously with minimum electron velocity. In this way the action of minimum-velocity electrons in impairing the efficiency of the electron-bunching phenomenon is greatly reduced, since fewer of these minimum-velocity electrons are produced than in prior art devices. On the other hand, the average- and maximum-velocity electrons are increased in number relative to the minimum-velocity electrons, so that their useful contribu-

tion to the electron-bunching process is enhanced. For these reasons greater efficiency and output is experienced by use of the present invention over prior frequency multipliers in which pure velocity modulation was utilized without any simultaneous or prior current variation.

The devices shown in Figs. 1 and 2 incorporate a lumped-constant type tuned input circuit 71, 73. This type of circuit is advantageous where the fundamental frequency is of the order of magnitude of 200 megacycles per second or less, and permits the use of fundamental frequency sources of conventional and well-understood type which may be multiplied in frequency by factors of from ten to thirty by the device of the present invention. However, where the fundamental frequency becomes higher than approximately 200 megacycles per second, the radiation inherently experienced adds a troublesome dissipative factor to the input circuit. In addition, the dimensions of the inductance and capacitance elements become impracticable.

The present invention is not restricted to the use of lumped-constant input circuits, as shown in Fig. 2, but may also utilize a cavity resonator for the input circuit where such higher fundamental frequencies are utilized. Such a device is shown in Fig. 3, where identical elements are given the same reference numeral, and corresponding elements are given corresponding but primed reference characters. As will be seen, the only difference between the devices of Figs. 2 and 3 is in the input circuit and manner in which the fundamental frequency electric field is superimposed upon the unidirectional electron-accelerating electric field between the cathode and the accelerating grid.

In Fig. 3, the cathode 77' is shown illustratively as formed by an emissive button or disc supported within a supporting conductive cylinder 41 with which is positioned the cathode heater shown schematically at 42 and supplied with heating energy from a suitable source such as a battery 43. Cathode 77' is connected to one of the heater terminals by a connecting link shown at 44, and is thereby directly connected to the negative terminal of the accelerating voltage source 68 whose positive terminal is grounded at 67 as in Fig. 1.

Surrounding cathode 77' is an input cavity resonator 46 formed by an outer cylindrical wall 47, an inner cylindrical wall 48, a first connecting end wall 49 connecting walls 47 and 48, and a second end wall 51 connecting wall 47 to the grid 69 and drift tube 75. Inner wall 48 is insulated from the cathode supporting cylinder 41 as by the insulating seal 78' which also serves to complete the vacuum envelope of which resonator 46 now forms a part.

In order to reduce the physical size of the resonator 46 for its given fundamental resonant frequency, a flange member 52 is supported on the inner wall 48 opposite the end wall 51, and, if desired, also opposite the outer cylindrical wall 47, as shown at 152. This flange 52 provides an effective lumped capacitance which permits the use of practicable sizes of resonator 46 even for relatively low fundamental frequencies. No tuning means is shown for resonator 46, but it is to be understood that any conventional type of tuning means permitting adjustment of the resonant frequency of this resonator may be utilized.

The fundamental frequency voltage f derived from the source 74' is coupled to the input resonator 46 by a suitable sealed coaxial line terminal arrangement 53 terminating within resonator 46 75

in a coupling loop 54, thus exciting resonator 46 in a conventional manner. Because of the capacitive coupling between inner cylindrical wall 48 and the cathode supporting cylinder 41, the excitation of resonator 46 at fundamental frequency produces a substantially uniform fundamental frequency alternating electric field between cathode 77' and grid 69. In addition, the battery 68 produces a substantially uniform unidirectional and constant electron-accelerating electric field between cathode 77' and grid 69. Accordingly, the electrons emitted from cathode 77' under the influence of the heat produced by heater 42 are projected through the grid 69 as in Figs. 1 and 2, and experience the same changes in current and velocity as discussed with respect to Figs. 1 and 2. Accordingly the apparatus of Fig. 3 will operate in exactly the same manner as that of Figs. 1 and 2 and will produce the same advantages discussed above.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A frequency multiplier electron discharge tube comprising a source of electrons, means for forming said electrons into a stream and including an accelerating electrode aligned with the path of said stream, means coupled to said source and electrode and comprising apparatus tuned to and adapted to be excited at a predetermined frequency for causing said electrons to form recurrent bunches, and means along the path of said stream and comprising a cavity resonator tuned to a harmonic of said predetermined frequency for extracting energy from said bunched electrons.
2. High frequency electron discharge tube apparatus comprising an electron-accelerating electrode and a high potential cathode, means for applying a high frequency voltage between said electrode and said cathode, said means including a coupling loop having one end connected directly to said grounded electrode and its other end capacitively coupled to said cathode, said loop being a hollow tubular conductor, and potential supply leads for said cathode disposed within said tubular conductor, whereby said leads are shielded from high frequency fields.
3. The combination as claimed in claim 2, wherein said leads enter said tubular conductor near the low alternating potential point thereof, whereby high frequency pick-up in said leads is minimized.
4. A frequency multiplier apparatus, comprising a source of electrons, means for projecting electrons from said source in the form of a stream and including a grid aligned with the path of said stream, a tuned circuit connected between said source and said grid, and a cavity resonator along said stream path and coupled to the stream passing through said grid, said resonator having a resonant frequency which is a harmonic of the resonant frequency of said tuned circuit.
5. High frequency apparatus comprising means including a cathode and an accelerating electrode for producing a stream of electrons, a resonant circuit intercoupling said cathode and accelerating electrode for simultaneously varying the magnitude of said stream and the velocities of

the electrons of said stream at a fundamental frequency, means along the path of said varied stream for causing said varied stream to become velocity-grouped, and means along said stream path for extracting energy from said velocity-grouped stream at a harmonic of said fundamental frequency.

6. High frequency apparatus comprising means including a cathode and an accelerating electrode for producing a stream of electrons, a resonant circuit intercoupling said cathode and accelerating electrode for varying both the magnitude of said stream and the velocities of the electrons of said stream at the same fundamental frequency, and means along said stream path for extracting energy from said varied stream at a harmonic of said fundamental frequency. 15

7. High frequency apparatus comprising a cathode, a grid adjacent said cathode, a source of potential connected between said cathode and said grid to form an electron stream flowing through said grid, tuned circuit means coupled between said cathode and grid and tuned to a fundamental frequency for varying both the current magnitude and the velocities of the electrons of said stream at a fundamental frequency, a drift tube surrounding the path of said stream beyond said grid, and an output resonator positioned along the path of said stream beyond said drift tube and tuned to a harmonic of said fundamental frequency for extracting harmonic frequency energy from said stream. 20

8. Apparatus as in claim 7, wherein said tuned circuit means comprises an inductance and capacitance connected in parallel and coupled between said cathode and grid. 35

5
10

9. Apparatus as in claim 7, wherein said tuned circuit means comprises a cavity resonator tuned to said fundamental frequency.

10. High-frequency apparatus comprising means including a cathode and an accelerating electrode for producing a stream of electrons, a tuned input circuit coupled to said cathode and electrode, a pair of output electrodes aligned with the path of said stream and spaced from said accelerating electrode, and an output circuit coupled to said output electrodes, said output circuit being tuned substantially to a harmonic of the resonant frequency of said input circuit.

11. Apparatus as in claim 10 further including a drift tube member surrounding said stream path and conductively connected between said accelerating electrode and one of said output electrodes. 15
